UNITED STATES PATENT OFFICE

EDWARD KANTER, OF CLEVELAND HEIGHTS, OHIO

DESIGN FOR A COMBINATION FOUNTAIN PEN HOLDER AND STATUETTE

Application filed October 12, 1931. Serial No. 41,368. Term of patent 3½ years.

To all whom it may concern:

Be it known that I, EDWARD KANTER, a citizen of the United States, residing at Cleveland Heights, in the county of Cuyahoga and State of Ohio, have invented a new, original, and ornamental Design for a Combination Fountain Pen Holder and Statuette, of which the following is a specification, reference being had to the accompanying drawings, forming part thereof, wherein—

Fig. 1 is a front elevation; Fig. 2 a top plan view and Fig. 3 is a side elevation of a combination fountain pen holder and statuette showing my new design.

I claim:—

The ornamental design for a combination fountain pen holder and statuette as shown.

EDWARD KANTER.
